UNITED STATES PATENT OFFICE.

HUBERT WITTE, OF ST. LOUIS, MISSOURI, ASSIGNOR TO ST. LOUIS CAR COMPANY, OF ST. LOUIS, MISSOURI, A CORPORATION.

GATE FOR CAR-PLATFORMS.

SPECIFICATION forming part of Letters Patent No. 783,739, dated February 28, 1905.

Application filed May 21, 1904. Serial No. 209,097.

To all whom it may concern:

Be it known that I, HUBERT WITTE, a citizen of the United States, residing in the city of St. Louis, in the State of Missouri, have invented certain new and useful Improvements in Gates for Car-Platforms, of which the following is a full, clear, and exact description, reference being had to the accompanying drawings, forming part of this specification.

My invention relates to a folding gate for the platforms of cars, especially those of street-railway cars.

Figure I is a side elevation of my gate in closed condition. Fig. II is a top or plan view of the gate, shown in full lines in closed position and in dotted lines in open position. Fig. III is an enlarged side view of the upper hinge connecting the two sections of my gate and the catch members by which the sections are locked in alinement with each other when the gate is in open position. Fig. IV is an enlarged horizontal section taken on line IV IV, Fig. I.

5 A designates the rear section of my gate, and B the forward section. The section A consists of a plurality of upright rods 1, the ends of which are connected to a yoke 2, that at its rear portion serves as an upright hinge-rod 3. This hinge-rod passes loosely through a pair of hinge-brackets 4, secured to the dashboard-wall at 5, as seen in Figs. I and II.

6 designates collars fixed to the hinge-rod and resting upon the hinge-brackets 4 to support said rod, and consequently the gate-section A.

7 designates hinge-sections that are secured to the upper and lower forward ends of the rear-gate-section yoke 2. These hinge members are provided with eyes 8, that receive a hinge-rod 9, which passes vertically therethrough, the eyes of the hinge-sections being at the outermost sides thereof and the hinge members have heels that are located inwardly from said eyes.

45 The gate-section B consists of vertical rods 10, that are mounted within a yoke 11. At the rear ends of the arms of the yoke 11 are hinge members 12, that are provided with eyes corresponding to the eyes of the hinge mem-

bers 7. When the hinge members 12 are associated with the hinge members 7 and the hinge-rod 9 is passed therethrough the sections A and B are so jointed together that they may swing in one direction only, which direction is inwardly over the car-platform at the center of the gate when the gate is moved from an unfolded and closed position to a folded and open position, or reversely when the gate is open and is being closed. It will be seen that by the described construction of hinge connection between the gate-sections it is impossible for the gate to be moved outwardly at the juncture of its sections beyond a point in which the sections are in alinement, as seen in Fig. II.

13 is a keeper-tongue that enters into a socket 14, appropriately located in the car-wall for the reception of said tongue, so that the gate will be held with its sections in alinement when in a closed position.

For the purpose of preventing the gate-sections from swinging inwardly at the point of their hinged connection I provide a pair of spring-catches 15 and 16, that are supported by hangers 17, depending from the hinge members 7 and 12. These catches are provided at their free ends with hook-noses 15' and 16', that are adapted to engage with each other when the gate is in unfolded condition, as seen most clearly in Fig. IV. By the provision of these catches it will be seen that when they are sprung into engagement in the unfolding of the gate their noses become interlocked, and therefore owing to the catches being located at the inner sides of the gate-sections and opposite the pivotal point of said sections the hinge connection between the sections is positively locked. When it is desired to fold the gate, the spring-catches may be readily disengaged by springing them away from each other, after which the sections of the gate may be readily swung on their hinge-rod 9 into folded condition to be moved inwardly to the dashboard-wall of the car, as illustrated by dotted lines, Fig. II.

18 is a retaining-hook slidably positioned on one of the gate-section rods 10 and upheld by a pin 20 in said rod, the retaining-hook

being provided with a notch 19 to receive said pin and hold the hook in a set position. When the gate is folded and moved to the dashboard-wall, the retaining-hook is lifted and 5 its point is dropped into the eye of a bracket 21, secured to the car-dashboard wall to hold the gate from movement.

22 designates a top horizontal hand-rail 10 mounting the yoke 2, and 23 is a vertical hand-rail that is secured at its upper end to the top hand-rail and at its lower end to the bottom arm of the gate-section yoke 2, as seen most clearly in Fig. I. These hand-rails being provided on the gate to be grasped by a person 15 entering or leaving the car-platform are of the same utility as the hand-rails usually attached to the walls of cars at the entrance-ways of the car-platform, and therefore by providing the rails on the gate I dispense with 20 the necessity of providing them on the car-walls.

I claim as my invention—

1. In a car-platform gate, the combination of a pair of sections hinged to each other,

25 hinges for supporting one of said sections, and a retaining-hook slidably mounted upon one of said sections and adapted for engagement with a suitably-supported keeper, substantially as set forth.

2. In a car-platform gate, the combination 30 of a pair of sections hinged to each other and consisting of yokes and vertical rods, a retaining-hook slidably positioned on one of said vertical rods, and a stop-pin for upholding 35 said retaining-hook, substantially as set forth.

3. In a car-platform gate, the combination 40 of a pair of sections hinged to each other and consisting of yokes and vertical rods, a retaining-hook slidably positioned on one of said vertical rods, and a stop-pin for upholding 45 said retaining-hook; said retaining-hook being provided with a notch adapted to receive said stop-pin, substantially as set forth.

HUBERT WITTE.

In presence of—

H. F. VOGEL,
M. H. MURPHY.
